US00D937824S

(12) **United States Design Patent** (10) **Patent No.:** **US D937,824 S**
Ye (45) **Date of Patent:** **** Dec. 7, 2021**

(54) **ALL-IN-ONE COMPUTER**

(71) Applicant: **Lenovo (Beijing) Co., Ltd.**, Beijing (CN)

(72) Inventor: **Yizhou Ye**, Beijing (CN)

(73) Assignee: **Lenovo (Beijing) Co., Ltd.**, Beijing (CN)

(**) Term: **15 Years**

(21) Appl. No.: **35/509,662**

(22) Filed: **Sep. 29, 2019**

(80) **Hague Agreement Data**

Int. Filing Date: **Sep. 29, 2019**

Int. Reg. No.: **DM/208638**

Int. Reg. Date: **Sep. 29, 2019**

Int. Reg. Pub. Date: **Jun. 19, 2020**

(30) **Foreign Application Priority Data**

Mar. 29, 2019 (CN) 201930139116.7

(51) **LOC (13) Cl.** **14-02**

(52) **U.S. Cl.**

USPC **D14/307; D14/451**

(58) **Field of Classification Search**

USPC D6/300, 308, 310, 642, 643, 650.1, D6/653.15, 654.15, 657, 661, 675; D14/125-129, 132, 239, 336, 341, D14/373-377, 451, 301, 307, 371; D16/229, 235, 241

CPC G06F 1/1601; G06F 1/1605; G06F 1/162
See application file for complete search history.

(57) **CLAIM**

The ornamental design for an all-in-one computer, as shown and described.

DESCRIPTION

2.1 : Front

2.2 : Back

2.3 : Left

2.4 : Right

2.5 : Top

2.6 : Bottom

2.7 : Front Perspective

2.8 : Back Perspective

3.1 : Front

3.2 : Back

3.3 : Left

3.4 : Right

3.5 : Top

3.6 : Bottom

3.7 : Front Perspective

3.8 : Back Perspective

The broken lines shown in the drawings illustrate portions of the all-in-one computer that form no part of the claimed design.

1 Claim, 16 Drawing Sheets
